(57) **CLAIM**

The ornamental design for a connector for a modular structure, substantially as shown and described.

DESCRIPTION

FIG. 1 is a front perspective view of the connector for a modular structure;

FIG. 2 is a plan view of the connector for a modular structure of FIG. 1;

FIG. 3 is a bottom view of the connector for a modular structure of FIG. 1;

FIG. 4 is a front view of the connector for a modular structure of FIG. 1;

FIG. 5 is a back view of the connector for a modular structure of FIG. 1;

FIG. 6 is a side elevation of the connector for a modular structure of FIG. 1;

FIG. 7 is a side elevation from the opposite side to FIG. 6 of the connector for a modular structure of FIG. 1; and, FIG. 8 is a rear perspective of the connector for a modular structure of FIG. 1.
